UNITED STATES PATENT OFFICE.

HUGH W. WATSON, OF GRAND ISLAND, NEBRASKA, ASSIGNOR OF ONE-SIXTH TO
SABURO SHINDO AND ONE-SIXTH TO GUY F. TANNER, BOTH OF GRAND ISLAND,
NEBRASKA.

CEMENT-POST MOLD.

1,260,105.

Specification of Letters Patent. Patented Mar. 19, 1918.

Application filed July 16, 1917. Serial No. 180,913.

To all whom it may concern:

Be it known that I, HUGH W. WATSON, a citizen of the United States, residing at Grand Island, in the county of Hall and 5 State of Nebraska, have invented certain new and useful Improvements in Cement-Post Molds; and I do declare the following to be a full, clear, and exact description of the invention, such as will enable others 10 skilled in the art to which it appertains to make and use the same.

My invention relates to improvements in devices for molding cement posts and the like, the principal object being to provide a 15 device of this character so constructed that a large number of posts may be molded in a device of minimum size, the mold being invertible so that a number of posts may be formed on each side thereof.

20 Another object is to provide a mold of the class specified which may be easily and inexpensively manufactured and marketed, yet one which will be easy to operate and will produce good results.

25 With the foregoing general objects in view, the invention resides in the novel features of construction and unique combinations of parts to be hereinafter fully described and claimed, the descriptive matter 30 being supplemented by the accompanying drawings which form a part of this specification and in which:

Figure 1 is a perspective view of the improved mold in operative position;

35 Fig. 2 is a similar view with one side of the mold removed for filling the same;

Fig. 3 is a transverse section;

Fig. 4 is a vertical longitudinal section; and

40 Fig. 5 is a perspective view showing a slightly different form of construction.

In the drawings above briefly described, the numeral 1 designates the body of the improved mold, said body being formed of a 45 metal plate, of a plurality of metal plates, or of boards, as occasion may demand. It will be observed body 1 is corrugated in order that a plurality of longitudinal grooves 3 are formed in the opposite side thereof, the 50 grooves at one side being positioned between those of the other side as shown. It is within the grooves or channels 3 that the posts are molded and if these posts are to be of uniform size throughout their lengths, the 55 grooves will be so shaped, but if the posts

are to be of greater width at their lower ends than at their upper ends, one end of the several grooves will necessarily be wider than the other end thereof, as illustrated at 3rd in Fig. 5. If this construction is followed, the small ends of alternate grooves will be positioned between the large ends of the intervening grooves to facilitate manufacture.

A pair of horizontally elongated end 65 members 4, constructed either of wood or metal or of any other preferred material, are permanently secured to the ends of the body 1 so that the ends of the grooves or channels 3 are closed, thus forming a plurality of troughs in which the posts are molded. The end members 4 project beyond the side edges of the body 1 and are formed with openings 5 through which horizontal rods 6 are passed, said rods extending 70 through longitudinal beads 7 which are formed along the ends of a pair of side members 8, said members being constructed of wood or metal as occasion may demand. Although the specific means described, are 75 preferably employed for securing the side members 8 over the channels of the body 1, it will be obvious that other suitable features of construction could well be employed for this purpose. I do not therefore wish to 80 be limited to such unessential details.

In operation, the improved mold is positioned horizontally and one of the rods 6 is removed so that the uppermost side member 8 may be swung upwardly around the other 90 rod as a pivot. The uppermost channels 3 are now filled with the green cement, of which the posts are to be constructed, reinforcing wires being by preference located in or near the corners of said posts during 95 the molding operation. After filling the channels, the upper side member 8 is again closed and locked in operative position by reinsertion of the rod 6 which was previously removed. The entire device is now 100 inverted, the ends of the members 4 being preferably rounded to assist in this operation, and in its inverted position, the mold is by preference supported on a plurality of suitable sleepers which will prevent the 105 cement resting on the side member 8 from possible springing or warping the same. These preliminaries having been carried out, what was previously the bottom side member 8 is raised in the manner above described 110

so that the now uppermost channels may be filled. This having been done, the side member last detached is again secured in place until the cement has set. When this 5 hardening has taken place, however, the rods 6 of the lowermost side members are removed, whereupon the mold is inverted, thus leaving a plurality of completed posts supported upon said side member. After 10 inverting the mold in this manner, the other rods are removed so that the remaining side member may be disconnected from the body of the mold, whereupon the latter is lifted and positioned at some out-of-the-way location, until the several completed posts have 15 been removed from the side members 8, to render the device in condition for further use.

Any suitable provision may be made for 20 securing the fence to the posts while molding the latter, but I prefer to provide the side members 8 with longitudinal slits 9 through which staples or the like may be inserted into the green cement, said staples 25 serving to receive any preferred fastening means by which the fence is to be secured to the post. These slits 9 may extend only throughout part of the width of the side members 8 or throughout substantially the 30 entire width thereof, according to the style of fence to be employed. Furthermore, it will be obvious that a number of individual openings could well be provided to permit insertion of the staples wherever required. 35

By constructing and operating the improved mold as or substantially as above described, a large number of posts may be cast in the same device with ease. Particular 40 emphasis is laid upon the fact that the body 1 is corrugated so that the opposite sides thereof produce the same effects upon the posts being cast. It is also worthy of note that the posts will be of triangular

shape. This shape has proven equally as 45 effective as others, and more advantageous in some respects, since it permits the completed articles to be removed from the molds more easily than round or square posts.

On account of the several advantageous 50 features of the construction above described, this construction constitutes the preferred embodiment of my invention. I wish it understood, however, that numerous minor changes may well be made within the scope 55 of the invention as claimed.

I claim:—

1. A mold of the class described comprising a body member having channels in its opposite sides, a pair of end members applied to the ends of said body member and closing the ends of said channels, said end members extending beyond the edges of said body member and having openings, a side member applicable for closing the channels 60 at one side of said body member and having guides in alignment with the openings of said end members, and a fastening rod insertable through said openings and guides for detachably securing said side member 65 in place.

2. A cement post mold comprising a body formed of a single sheet of metal corrugated to provide its opposite sides with plastic receiving channels, end plates secured to the ends of said body and closing the ends of said channels, a pair of side plates for covering the channels at the upper and lower sides of said body, and means 75 for securing said side plates in place.

In testimony whereof I have hereunto set my hand in the presence of two subscribing witnesses.

HUGH W. WATSON.
